UNITED STATES PATENT OFFICE

MARY D. NEILSON, OF MINNEAPOLIS, MINNESOTA

UNDERGARMENTS FOR WOMEN SUCH AS SLIPS, PAJAMAS, BLOUSES, AND THE LIKE

Application filed July 14, 1930. Serial No. 467,815.

My invention relates to garments for women, such, for example, as slips, pajamas, blouses and the like. It is the object of the invention to provide a garment of that type 5 wherein the fullness around the bust of the wearer is so taken care of that the garment will hang straight from the shoulders at the rear and straight from the bust line at the front, and the bottom of the garment will 10 continue even and horizontal all around. I accomplish these objects by a novel and heretofore unknown method of taking up material by a series of small pleats in the front of the arm scye of the garment along the 15 curve extending from the side seam.

In any garment worn by a woman the fitting of the garment for the upper part of the figure requires extra length in the front of the garment at the bust line to allow for the bust fullness, since the figure rounds out at this point and the line from the top of the shoulder to the waist line in front must be longer than the line from the top of the shoulder to the waist line in the back. It follows 20 that if the garment is made with front and back of the same length, the fullness of the bust requiring this necessary extra length, will pull the garment up in front and cause it to hang down and in at the back and up 25 and out at the front. This is an awkward and undesirable condition and one which my invention is designed to correct. It is undesirable not only for appearance, but also for feel. The wearer will 30 constantly keep trying to adjust her garment to the line of her figure by pulling it down in front. But even when it is pulled down it will never stay down, because from the manner in which it is cut it does not belong 35 down.

The full objects and advantages of my invention will appear in connection with the detailed description thereof, and its novel features are particularly pointed out in the 40 claims.

In the drawing, illustrating the application of my invention,

Fig. 1 shows a manikin figure having a 45 sleeping garment worn thereon and showing the manner in which the front and back and

bottom line of the blouse hang with reference to each other and to the wearer. Fig. 2 is a manikin wearing a slip embodying the features of my invention. Fig. 3 shows a cut-out blank illustrating half of the front of 55 the garment. Fig. 4 shows this blank after the adjustments embodying my invention have been applied thereto.

The garment 20 (blouse of pajamas), illustrated in Fig. 1, and the garment 21 (full 60 length slip), illustrated in Fig. 2, are constructed alike so far as the fitting characteristics about the bust and shoulder members go, the principal or only difference being in 65 the length of the pieces to make the garment. Fig. 3 illustrates the form of a front 70 of the blouse 20. It may be cut in two pieces and seamed as at 22 or, as more commonly in practice, it may be cut in a single piece and folded at 22. Fig. 3 illustrates the piece before my invention is applied thereto wherein the front cut-out to fit in the neck is shown at 23 and the arm scye at 24. In the original blank the arm scye extends from *a* to *b* a certain definite length, which is greater than 75 the arm scye should be, that is such as to give extra length to the garment at that point, and which extra length is taken care of in the manner hereinafter described. In the lower part of the curve of the arm scye I 80 introduce a number of small pleats 25. Four are shown, which is a satisfactory arrangement, but a greater or less number may be employed with satisfactory effect. The result 85 of putting the pleats in in this manner will be to shorten the distance from *a* to *b* to that shown in Fig. 4 as running from *c* to *d* to change the curve of the arm scye 24 and draw back the neck cut-out 23 and the shoulder seam piece 26, also curving the front portion 22 as indicated at 27, all as shown in Fig. 4.

When, therefore, the parts 23 and 26 are lifted in the fabrication of the garment to the position shown in Fig. 1, it will have the effect of throwing the extra length and excess material of the arm scye 24 taken up by the pleats 25 forward across the busts, leaving the front and back lines 28 and 29 of the garment hanging straight and parallel and the bottom line 30 horizontal, as shown in 90 95 100

Fig. 1. By this means, extra material is distributed in a manner to give the effect of swinging the garment around the busts from the straight hanging line in front to the straight hanging line in the back, and that makes possible a hang to the garment such as is shown in Fig. 1.

The advantages of such a garment hanging in that way are very marked and produce an effect which I believe never has been produced before. This effect also is produced by simple and efficient means, easily applied, and not adding to the expense of the garment. The effect does not, however, appear from casual consideration, but is only made evident by demonstration.

I claim:

1. A garment for women wherein each front section is cut with parallel side edges and extra length of material at the arm scye, the said arm scye extending in a continuous curve from the shoulder seam to the side edge of the front, said curve being accentuated adjacent to said edge, and said extra length of material being reduced by a pleat extending in reverse radial direction inwardly from a point adjacent to the center of said accentuated part of the curve of the arm scye.

2. A garment for women wherein each front section is cut with parallel side edges and extra length of material at the arm scye, the said arm scye extending in a continuous curve from the shoulder seam to the side edge of the front, said curve being accentuated adjacent to said edge, said extra length being reduced by a multiplicity of pleats extending in a radial direction inwardly from said accentuated curve portion of the arm scye.

In testimony whereof I hereunto affix my signature.

MARY D. NEILSON.
